UNITED STATES PATENT OFFICE.

WILLIAM DUBOCQ, OF NEW YORK, N. Y.

STREET-SWEEPER.

1,122,702.

Specification of Letters Patent. Patented Dec. 29, 1914.

Application filed June 12, 1913. Serial No. 773,208.

To all whom it may concern:

Be it known that I, WILLIAM DUBOCQ, a citizen of the United States, and a resident of the borough of Queens, county of Queens, 5 city and State of New York, have invented certain new and useful Improvements in Street-Sweepers, of which the following is a specification.

This invention relates to street sweepers which both sweep and remove the dirt from the street during the same operation, and particularly concerns that type of sweepers shown in U. S. Letters Patent to A. H. Smith #633,296 and to W. Brady #634,283, 15 and the object of this invention is the devising of improvements upon such and kindred constructions, as more fully appears in the following description and concluding claims.

20 The sweepers comprised in the above-mentioned Letters Patent operate in the usual way to sweep the dirt, for instance, from the curb toward the center but instead of sweeping it in the usual way in a long ridge, it is thrown from one end of the brush into buckets carried within the periphery of a revolving drum. While, with such devices, nearly all of the dirt is thrown into the buckets, nevertheless a small ridge is left behind resembling the slight indication of dust left 25 along the edge of a dust-pan. This of course will be swept along during the sweeping operation of the next strip of road-bed but when the last strip of road-bed is swept 30 the "dust-pan" line, which is about the height of the thickness of the receptacle in contact with the road-bed into which the sweepings are thrown by the brush, is still left behind. While this is comparatively in- 35 appreciable in amount, it presents nevertheless a very objectionable appearance, and has detracted much from the practicability of such sweepers. In my invention I have abandoned attempting to get this "dust-pan" 40 line into the buckets, but have provided means for promiscuously blowing this small amount of the sweepings about the street; for, while collected in a ridge it presents a serious objection, yet it is so inappreciable 45 in amount that it can easily be blown about without being noticed.

In the style of sweepers comprised in the 50 patents referred to the revolving brush is driven from the axle carrying the buckets. This axle also supports one of the wheels of the vehicle, while the wheel opposite is sup-

ported by another axle. The former wheel carries by far the greater load and added to this the work of driving the brush produces an unequal distribution of the work to such 60 an extent that the sweeper has a tendency to skid and thereby produce an uneven edge of sweepings. This unevenness made it necessary for the operator to include a narrower strip of the unswept road-bed at his next 65 sweeping operation in order to include the uneven edge, thereby decreasing the efficiency of the sweeper. The wheel carrying the buckets also forms the pivot about which the vehicle turns after it has swept the 70 length of the street and is being turned around to sweep back over the next strip. During this pivotal action of the wheel the brush does not appreciably revolve, but instead drags along the road-bed without producing any effective sweeping. I have overcome this difficulty and also the objectionable feature of skidding by driving the brush through transmission mechanism from the wheel opposite to that supporting 75 the buckets thereby more nearly equalizing the work of the two wheels.

The buckets as they revolve gradually assume inverted positions in order to permit them to drop their contents into a chute provided for that purpose, from which the sweepings fall by gravity to a retainer. During this gradual inversion of the buckets more or less of their contents fall from them before they reach the chute. Some of 85 the sweepings also clings to the sides of the buckets after they have passed the chute, especially when the road has been previously sprinkled. I improve upon the former objectionable feature by securing a side of each 90 bucket at a suitable angle which aids in holding back the sweepings until the buckets are above the chute. Positive means are also provided for cleaning each bucket before it leaves the space above the chute. 95

The various other objects of the invention will be more fully set forth in the following description of one form of mechanism embodying the invention which consists in the new and novel features of construction and 100 combination of parts hereinafter set forth and claimed.

Referring to the drawings—Figure 1 is a plan view, partly in section, of a sweeper embodying my improvements. Fig. 2 is an 110 elevation, viewed from the back of the sweeper. Fig. 3 is a sectional view of the

rear portion taken on the line III—III of Fig. 1 looking in the direction of the arrow, and Fig. 4 is a fragmental sectional view on the line IV—IV of Fig. 3.

5 The vehicle in the main resembles that shown in U. S. Letters Patent No. 634,283 before referred to, and will therefore only be described in a general way as to those parts resembling the sweeper there shown.

10 The vehicle body 1 is supported on front wheels 2 and rear wheels 3 and 4. As shown, the sweeper is intended to be drawn by horses, but it is obvious that it could be a motor vehicle if desired, or it could be drawn 15 by a motor vehicle instead of horses.

A brush 5 is revolvably mounted in brackets 6 supported by the body 1 from pivotal connections 7, whereby the brush may be raised and lowered from and to the road-bed and revolved within its bracket journals. A shield or apron 8 is secured to the brackets 6 immediately in front of the brush to confine the sweepings between it and the brush. The brush is set at a suitable angle to the 20 direction of travel of the vehicle to induce the sweepings to gradually work toward the rearwardly positioned end of the brush. A lever 9, pivoted to the body 1, is connected at one end to the shield 8 and has its other 25 end positioned at a convenient distance from the seat 10 to facilitate its being raised and lowered by the operator. The wheel 3 is secured upon an axle 11 journaled in the side members 12—13 of a side extension 14 of the 30 vehicle body, the wheel 3 being the one intended to travel along the curb during the sweeping of the first strip and thereafter adjacent the portion of the street already 35 swept.

40 A bevel gear 15 is secured to the axle 11 and engages a bevel gear 16 secured on a shaft 17 journaled in the extension 14 parallel to the brush 5. A shaft 18 is rotatably mounted upon a support 19 rigidly connected to the brackets 6 and is driven from the shaft 17 through the intervention of sprocket wheels 20 secured on the respective 45 shafts and the chain 21. The shaft 18 is in driving engagement with the shaft 22 of brush 5 through the intervention of sprockets 23—23 secured on the respective shafts and the chain 24.

The wheel 4 is secured upon a stub axle 25 rotatably mounted in the side members 55 26—27 of an extension 28 of the vehicle body 1 opposite the extension 14.

60 A cylindrical drum 29 is secured to the inner side of the wheel 4 and is open at its inner end to adapt it to receive the sweepings leaving the end of the brush which 65 preferably extends slightly within the drum. The drum has a flaring mouth-piece 30 of suitable diameter to bring it in contact with the road-bed to facilitate the sweepings from the brush entering the drum.

Buckets 31 are formed within the drum by securing partitioning plates 32 to the walls thereof. These partitions are inclined with respect to the head 33 of the drum to form buckets having acute angles at the juncture 70 of the walls formed by the drum-head and plates. A chute 34 is secured to the vehicle body in inclined position with its upper end extending within the drum near the top thereof and is of sufficient width to include 75 several of the buckets. The angularity given the plates 32 aids in holding the sweepings during the partial inversion of the buckets until they reach a substantially inverted position above the chute, at which 80 time the sweepings drop into the chute.

A plate 35 is preferably secured in advance of the chute to aid in holding the sweepings within the buckets during their 85 partially inverted positions before reaching the mouth of the chute and to deflect whatever sweepings may by chance fall from the buckets into the buckets below. The chute 34 is preferably turned up, as at 36, to check any sweepings that might otherwise be 90 thrown by the buckets beyond the chute.

The rear end of the vehicle body beneath the chute is considerably lower than the remainder of the body to provide a floor 37 upon which are placed receptacles 38 for receiving the sweepings from the chute. The extension 14 has a flooring 39 which is hinged to be raised and lowered in order to easily reach the mechanism below. This flooring provides additional room for storing a supply of receptacles, so that as one is 95 filled another can be placed beneath the chute. Other receptacles can be placed behind the driver's seat as sufficient room is provided there for that purpose.

100 A blower 40 is secured to the body 1 and connects with a line of piping 41 which extends to a point near the road-bed behind the brush and adjacent the flaring mouth-piece 30 of the drum. The piping terminates at 105 this point in a nozzle 42. The blower is driven from the shaft 18 by means of the sprockets 50—50 mounted on the shaft of the blower and the shaft 18 respectively and the engaging chain 51. The sprocket on the blower shaft is loosely mounted and has secured to it the clutch jaw 52. A clutch jaw 53 is slidably keyed to the shaft of the blower for engaging the jaw 52 as the former is slid upon its shaft. The jaw is operated 110 by a lever having an arm 54 engaging the jaw and pivotally mounted on a post 55 secured to the frame 1. The other arm 56 of the lever is suitably positioned to be in easy reach of the driver.

115 A bracket 43 is secured to the body 1 for supporting the bucket cleaning device. This 120 comprises a scraper 44 provided with a stem 45 rotatably mounted to swivel in a socket 46 extending from a sleeve 47 loosely mount- 125

ed on a shaft 48 secured to the bracket 43. The sleeve is spring-pressed against the partition and yieldingly held at the end of the shaft nearest the drum by means of a spring 49. While I have shown the receptacles 38 for receiving the sweepings they could be replaced by an endless carrier which could convey the sweepings from the chute to a wagon either at the front or rear of the 10 sweeper and this receiving wagon could also serve as the motor for the sweeper if found desirable.

In operating the sweeper the driver raises and lowers the brush when deemed necessary by means of the lever 9 in the usual manner. The blower is thrown out of operation by means of the lever arm 56 and the driver starts to sweep along the curb of the street continuing from one end to the 20 other of the street. Where barrels or other similar receptacles are used for receiving the sweepings, an attendant may be stationed on the floor 37 to tend to the filling and removal of the receptacles. At the end of the street 25 the driver turns the vehicle around and sweeps a strip along the opposite curb, the turning of the vehicle around operating to continuously rotate the brush and to sweep the dirt into the buckets. When the opposite end of the street is reached the driver again turns his vehicle around and sweeps a second strip along the opposite side of street swept. He continues in this way and when the last strip of road-bed is swept he 35 throws the blower into operation by means of the lever 56. This blows the "dust-pan" ridge of sweepings left behind on account of the thickness of the mouth-piece 30 promiscuously about the street.

40 During the entire sweeping operation the scraper 44 contacts with each of the partitions 32. It first engages the partitions at their top edges and continues in contact over the entire surface of the partitions as the 45 latter advance. The scraper swivels within the socket 46 which insures a uniform contact with the partition regardless of the angularity given it. The spring 49 serves to spring-press the scraper against the partition and also permits the sleeve 47 to be forced longitudinally along its shaft by the drum-head 33 as the partition in advancing 50 swings the scraper about the shaft 48, the

longitudinal movement being necessary on account of the angularity given the parts. 55 The scraper during its swinging movement from the full line to the dotted position shown in Fig. 3 scrapes the partition throughout its entire length, and moves any sweepings that might otherwise have clung 60 to the bucket. The dotted position (Fig. 3) shows the scraper just leaving one of the partitions. It then automatically swings back and at the same time moves longitudinally due to the tension and torsional condition of the spring 49 into its first position against the next partition whereupon the scraping operation is repeated. 65

Although I have shown only one form of mechanism embodying my invention, it is 70 obvious that various changes within the skill of the mechanic may be made therein without departing from the spirit of the invention, provided the means set forth in the following claims are employed. 75

Having thus described my invention I claim—

1. In a sweeping machine, a brush, a receptacle for receiving the sweepings from the brush having an edge adapted to contact with the surface being swept, and a blower having a nozzle at the rear of the brush and directed toward the edge of the receptacle at the point where it is adapted to contact with the surface being swept for 80 blowing the sweepings finally left by the receptacle promiscuously over the surface. 85

2. In a sweeping machine, a brush, a receptacle for receiving the sweepings from the brush having an edge adapted to contact 90 with the surface being swept, a blower having a nozzle at the rear of the brush and directed toward the edge of the receptacle at the point where it is adapted to contact with the surface being swept for blowing 95 the sweepings finally left by the receptacle promiscuously over the surface, and means for throwing the blower into and out of operation.

This specification, signed and witnessed 100 this 23rd day of May, A. D. 1913.

WM. DUBOCQ.
